UNITED STATES PATENT OFFICE

IRVIN W. DAVIS, OF SOUTH MILWAUKEE, WISCONSIN

LIMB REST STAND

Application filed July 2, 1930. Serial No. 465,397.

This invention relates to improvements in limb rest stands, and more particularly to a stand for the use of a hospital or surgeon for conveniently supporting a patient's limb 5 while the same is being dressed or operated on.

It is one of the objects of the present invention to provide a limb rest stand which will support a limb being worked on surgically, in a manner so that the desired portion of the 10 limb is held in an accessible position, said stand further being provided with a receptacle holder so that the portion of the limb being worked on is disposed directly over a receptacle therein to catch drippage, 15 or for holding equipment and the like.

A further object of the invention is to provide a limb rest stand of the class described which may be adjusted vertically, which may be swiveled, and which may be tilted to a 20 desired angle.

A further object of the invention is to provide a limb rest stand which may be manufactured easily and relatively inexpensively, which is extremely convenient in use, which 25 is strong and durable, and which is well adapted for the purposes described.

With the above and other objects in view the invention consists of the improved limb 30 rest stand, and its parts and combinations as set forth in the claims, and all equivalents thereof.

In the accompanying drawing in which the same reference characters indicate the 35 same parts in all of the views:

Fig. 1 is a side view of the improved limb rest stand;

Fig. 2 is a plan view thereof;

Fig. 3 is a longitudinal detail sectional 40 view taken on line 3-3 of Fig. 1, and on a larger scale;

Fig. 4 is an enlarged fragmentary view, partly in section, of the lower portion of the stand;

Fig. 5 is a detail view of a modified form of limb rest unit;

Fig. 6 is a fragmentary detail sectional 50 view showing a modified form of swivel block and bowl supporting ring adjustably held thereby, taken on line 6-6 of Fig. 7; and

Fig. 7 is a detail sectional view thereof taken on line 7-7 of Fig. 6.

Referring now more particularly to the drawing it will appear that the numeral 7 indicates an elongated tubular support formed from sheet metal rolled into tubular form of circular cross section. Said tubular support has formed in its wall vertically aligned and spaced-apart bayonet slots 8 connected by a vertical slot 9.

Telescopically mounted within said support 7 is an elongated tubular extension post 10, of circular form in cross-section, and adapted to be adjusted vertically through the open upper end portion of the support 7. Said post 10 is somewhat longer than the support 7.

There is mounted on the upper portion of the post 10, and spaced below the upper end portion thereof, a sleeve 11. A collar 12 is interposed between the upper end portion of the sleeve and the post 10 and said sleeve is secured to the collar and to the post by a pair of opposed set screws 13 threaded through all of said members and adapted to extend into the hollow post 10 for the purpose hereinafter to be explained. Said sleeve 11 is of a length sufficient to overlap the upper end portion of the support 7 when the post 10 is in its extended position.

Revolutely mounted about an upper portion of the post 10 and seating on the upper edge portions of the collar 12 and sleeve 11, is a swivel block 14 which is formed with a pair of opposed openings 15 to removably receive the depending angular end portions 16' of an annular bowl supporting ring 16. Said ring is for the purpose of removably holding or supporting a bowl or receptacle, as shown in dotted lines in Fig. 1 and indicated by the numeral 17.

The shank 18 of a yoke 19 extends revolutely into the upper end portion of the post 10 and the lower end portion of said shank is formed with an annular groove or recess 20 into which the inner end portions of said set screws 13 project. This arrangement prevents undesired vertical withdrawal of the yoke shank from said post and causes the yoke and shank to move vertically with the post

10 and sleeve 11 when vertical adjustments are made. However, said shank 18 is free to turn or swivel within the post 10. Also, by reason of a pair of opposed notches or recesses 36 formed in the lower flange 37 of the shank 18, said shank may be turned to bring said notches 36 into alignment with the set screws 13, and then said shank and yoke may be lifted vertically upwardly and be completely removed or withdrawn from the post 10 and associated parts.

Straddling the upper opposed end portions of the arms of the yoke 19 is a curved limb rest 21, of saddle-like formation, and its opposed depending arms 22 are adjustably secured to the arms of the yoke. Extended through one arm and adjacent yoke portion is a bolt or pivot stud 23 having a cotter pin 24 passed through its inner end portion. The other limb rest arm and adjacent yoke portion have extended therethrough an elongated bolt 25 whose shank portion has threaded thereon a winged nut 26, and between the nut and the yoke portion, surrounding the bolt shank, is a confined coiled spring 27, and the tension of the spring may be varied by adjusting the nut 26. The arrangement described permits the limb rest 21 to be tilted with respect to the yoke, and the ease with which it may be tilted, or its retention in a tilted position, may be controlled by the nut 26 and spring 27.

The lower end portion of the support 7 has wedged into slots therein, a pair of plate members 28 and 29, disposed at right angles to one another and medially crossing each other and having a mortise joint with each other. The projecting end portions of the plate members 28 and 29 have pivotally or hingedly secured thereto inner end portions of supporting legs 30, 31, 32 and 33. Said legs are of channel formation with their open portions faced downwardly, and secured within the outer end portions of the legs are stems 45 of casters 34. The hinge connections of the legs with respect to the plate members permits the legs to be folded so as to extend longitudinally of the member 7 when they are not in use for supporting purposes.

50 The improved limb rest stand is adapted to be positioned adjacent a chair in which a patient is seated, or other support for the patient. To adjust the stand to the proper height the sleeve 11 is grasped and it is turned until a headed stud 35 projecting laterally from a lower portion of the post 10 is brought into registration with the vertical slot 9 of the tubular support. Then, the post and parts attached thereto may be raised or lowered with respect to the support to the desired height, and the post is retained in the adjusted position by turning it and the sleeve to cause the stud 35 to drop into an adjacent bayonet slot 8. The limb rest 21 is then swiveled to the proper position of alignment and

tilted to the desired angle and the patient's limb is rested thereon and is comfortably supported thereby in a convenient position. The swivel block 15 is turned on the post so as to bring the ring 16 and receptacle carried thereby immediately below the projecting portion of the patient's limb.

In Fig. 5 a slightly modified form of limb rest is illustrated. In this form the limb rest proper 21' is of table-like formation and is rigidly carried by the upper end portion of the revoluble shank 18'.

A further modification is illustrated in Figs. 6 and 7. In this form the swivel block 14' is rectangular in outline and the post 10 extends centrally therethrough, with the block being turnable on the post. The block is formed with two opposed narrow slots 15' on opposite sides of the post opening, extending through the block from front to rear. Said slots are adapted to slidably receive arms 16'' which are rigidly secured to a bowl supporting ring 38, the arms projecting in spaced relation laterally from the ring. The upper edges of said arms are formed with a series of spaced notches 39 engageable with upper pins 40 within the slots 15'. The lower edges of the arms rest on pins 41 within said slots. It is therefore evident that this form of ring is horizontally adjustable with respect to the swivel block, and is also removable therefrom.

From the foregoing description it will be seen that the improved limb rest stand is of simple and novel construction, and is well adapted for the purposes set forth.

What I claim as my invention is:

1. An adjustable stand, comprising a vertical supporting member, legs foldably connected to the lower end portion of said supporting member, a post having a telescopic engagement with said supporting member, means for holding the post in positions of longitudinal adjustment with respect to the supporting member, a rest member adjustably and swivelingly carried by an upper portion of the post, and a receptacle holder swivelingly and removably carried by the post below the rest member.

2. An adjustable stand, comprising a supporting member, a post vertically adjustably carried thereby, a yoke member swivelingly carried by an upper portion of the post, a rest member tiltably carried by said yoke member, and a receptacle holder swivelingly mounted about said post below the rest member.

3. An adjustable stand, comprising a supporting member, a post vertically adjustably carried thereby, an adjustable limb rest swivelingly mounted about an upper portion of said post, and a receptacle holding frame swivelingly mounted about an upper portion of said post below the limb rest and removable from the post.

4. An adjustable stand, comprising a supporting member, a post vertically adjustably carried thereby, an adjustable limb rest swivelingly mounted about an upper portion of said post, a swivel block rotatably surrounding an upper portion of said post, and a receptacle holding frame member detachably carried by said swivel block below the limb rest and projecting laterally of the post.
- 10 5. An adjustable stand, comprising a vertical, tubular supporting member having a plurality of vertically spaced-apart bayonet slots formed therein and an elongated slot connecting all of said bayonet slots, a post extending out of the upper end portion of the supporting member and movable with respect thereto, a lower portion of said post carrying a laterally projecting pin movable in said elongated slot and lodgable in any of said bayonet slots for post supporting purposes, an elongated sleeve secured to an upper portion of said post, the upper end portion of said sleeve being below the upper end portion of the post, 25 a yoke member swivelingly carried by the upper portion of said post, a limb rest tiltably carried by said yoke member, a swivel block rotatably surrounding the upper portion of said post and seated on the top portion of 30 said sleeve, and a receptacle holding frame member detachably carried by said swivel block below the limb rest and projecting laterally of the post.
- 35 6. An adjustable stand, comprising a supporting member, a post vertically adjustably carried thereby, a limb rest adjustably carried by an upper portion of said post, and a receptacle holding frame horizontally and longitudinally adjustably connected with an upper portion of said post below the limb rest.
- 40 7. An adjustable stand, comprising a vertical supporting member, a post vertically adjustably carried thereby and adapted to be extended with respect to said supporting member, complementary means on the supporting member and post for quickly releasably retaining the post in an extended position with respect to the supporting member, a limb rest adjustably and swivelingly carried by an upper portion of the post, a slotted block mounted on an upper portion of the post below the limb rest, and a receptacle holding frame formed with a supporting arm, said supporting arm extending slidably, 50 adjustably into said slotted block and the frame being horizontally longitudinally adjustable with respect to the block below said limb rest.
- 55

60 In testimony whereof I affix my signature.
IRVIN W. DAVIS.
